UNITED STATES PATENT OFFICE.

CHARLES J. RECTOR, OF MONTEREY, CALIFORNIA, ASSIGNOR OF ONE-HALF TO
THOMAS L. O. FASSETT, OF SAN FRANCISCO, CALIFORNIA.

FELT-CUTTING TOOL.

Application filed December 1, 1924. Serial No. 753,305.

This invention relates to mechanics' hand tools of the character known as shears, snips or cutters, and it has for its principal object such a tool which will cut sheet felt and 5 similar fibrous material, particularly in the cutting out of washers and gaskets as so largely used in automobile work.

With an idea of giving a clear impression of just what the tool accomplishes so that its 10 following detailed description will be easily understood, it should be noted that in order to cut a washer from a very thick piece of felt, a pair of scissors cannot be used for if the felt is hard, they will not cut at all, and 15 there is no way by which they can be brought into action for cutting out the hole in the washer especially if the hole is but an inch or two in diameter.

There are revolving cutters which will do 20 the work on large felt washers but they are expensive, not readily portable, as they require to be used on a bench, and are not at all adapted to the cutting of other forms than round.

25 Consequently the mechanic always must resort to the use of a hard wood block with a chisel and hammer, or a sharp knife to ardously cut out the desired forms.

However, with the simple tool shown in 30 the accompanying drawings, a washer of any size, or any other shape, may be quickly and easily cut from the toughest felt, leather, rubber or other sheet material and by anyone with practically no experience.

35 In the drawings:—

Figure 1 is a perspective view of the complete tool drawn substantially full size with the lever as though depressed by an operator and the blade forced downward through 40 the anvil.

Figures 2 and 3 are detached front and side views of the plunger knife, and

45 Figure 4 is an enlarged front sectional view of the blade and anvil showing a modified sharpening of the cutting edge of the blade.

The device as shown in the drawings takes the form of a plier or punch like hand tool having a body 1 with a U-shaped handle 2 50 extending therefrom, and being bent at 3 to return under the body and formed into an anvil 4 to receive the cutting blade 5.

The cutting blade is secured to or formed 55 with a plunger portion 6 freely slidably through an opening formed in the body and

is positioned with its blade directed toward the anvil so as to snugly enter a slot 7 therein when the plunger is moved in a direction toward the anvil.

To operate the plunger, a lever handle 8 60 is provided which passes through a slot in the end of the plunger being pivoted to it at 9 and extending forward of the plunger and pivoted at 10 to a link 11 in turn pivoted at 12 to a horn 13 extending forwardly from 65 the body.

Surrounding the plunger is a spiral compression spring 14 reacting between the top of the body 1 and a pin 15 projecting from the plunger and which spring serves to normally hold the plunger and lever raised to the position indicated by the dotted lines so that the point only of the blade will project 70 from the body.

The space between the upper and lower 75 portions of the U handle is large enough to receive the fingers of the operator's hand and in addition the thickest sheet of material which it is desired to cut, so that a large sheet of material may extend thereinto below the fingers in manipulating the device in cutting a large washer, tho in hard cutting on smaller pieces of material, the fingers of the operating hand may grip the under run of the U handle with the thumb portion of the hand placed over the lever 8 for forcing the blade through the material into the anvil and thereby serve also to steady the anvil against deflection due to an 80 abnormally hard cut.

90 The slot 7 in the anvil is preferably somewhat longer than the width of the blade, a snug fit for the thickness of the blade and the cutting edge of the blade is formed at an outwardly slanting angle to receive the material and with a point at its inner edge.

95 The cutting edge in relation to the anvil edges may vary somewhat with different usage, and Figures 2 and 3 show a single shear blade which would have a cutting action against one side of the anvil slot, whereas Figure 4 shows a square edge blade 5" having a shearing action against both edges of the anvil.

100 The rearwardly slanting blade with point 105 as shown in Figure 1 at 5' is of great importance for the point is used to locate the beginning of the cut and the material is fed with the left hand into the tool against the slanted edge while the plunger is operated 110

like a punch by the right hand gripping the handle 2 and lever 8 as described.

Thus, a cut can be started at any point within a sheet of material, such as for instance, the cutting out of a hole in a felt washer, and with the greatest facility the cut may be given any required curve by guiding the material in the desired direction against the blade while working the reciprocating blade up and down through it, in fact with the leverage of the tool shown, felt a quarter of an inch or more in thickness can be handled about as easily as paper with an ordinary pair of scissors.

15 The lever 8 extending through the slotted portion of the plunger prevents same from turning out of alignment with the slot in the anvil and is a simple way of overcoming any necessity of splining the plunger to the body, tho this may also be resorted to if desired.

I claim:—

1. A mechanic's tool of the character described comprising a body, a flat blade reciprocably mounted in an opening through the body, a U-shaped handle extending from the body and with one leg of the U returning under the blade and slotted to receive the blade upon reciprocation of the same, and hand operated means cooperating with the handle for reciprocating the blade.

2. A mechanic's tool of the character described comprising a body, a flat blade reciprocably mounted in an opening through the body, a U-shaped handle extending from the body and with one leg of the U returning under the blade and slotted to receive the blade upon reciprocation of the same, an extension from the body, a link pivoted to the extension, a hand lever pivoted to the link and connected to the blade, said hand lever extending in cooperative relation to the handle for manual operation.

3. A mechanic's tool of the character described comprising a body, a flat blade 45 mounted for reciprocation therethrough, a pivoted lever operatively connected for reciprocating the blade, a handle extending from the body adapted to cooperate with the lever for gripping the tool, said handle being 50 of U form with one leg secured to the body and the other returning under and forming an anvil for the blade with a space between the legs of the U adapted to receive sheet material being cut by the blade. 55

4. A mechanic's tool of the character described comprising a body, a flat blade mounted for reciprocation therethrough, a pivoted lever operatively connected for reciprocating the blade, a handle extending 60 from the body adapted to cooperate with the lever for gripping the tool, said handle being of U form with one leg secured to the body and the other returning under and forming an anvil for the blade with a space 65 between the legs of the U adapted to receive the fingers of the hand operating the tool and also sheet material being cut by the blade.

5. A mechanic's tool of the character described comprising comprising a body with an opening therethrough, a plunger reciprocable in the opening, a flat blade secured to one end of the plunger, a hand lever pivotally supported from the body pivotally connected to 70 the opposite end of the plunger, a handle extending from the body adapted to cooperate as a grip for operating the handle with one hand, an extension from the handle forming an anvil for the blade slotted to receive the 75 same in reciprocation, and a spiral spring around the plunger reacting against the body adapted to move the plunger and blade away from the anvil. 80
